Primary Examiner—Alan P. Douglas*Assistant Examiner*—M. N. Pandozzi*Attorney, Agent, or Firm*—Bell, Seltzer, Park & Gibson[57] CLAIM

The ornamental design for a portable food tray with cup holder, as shown and described.

DESCRIPTION

FIG. 1 is a perspective view embodying the new design; FIG. 2 is a top plan view thereof; and, FIG. 3 is a sectional view thereof taken along line 3—3 of FIG. 2.

The broken line showing of a cup in FIG. 3 is for illustrative purposes only and forms no part of the claimed design.

1 Claim, 1 Drawing SheetFIG. 1.

FIG. 3.
